APPARATUS FOR SLOTTING AND CUTTING PIPE

Morris Muskat, Oakmont, Pa., Floyd W. Parker, Harrogate, Tenn., and William L. Kehl, Penn Township, Allegheny County, Pa., assignors to Gulf Research & Development Company, Pittsburgh, Pa., a corporation of Delaware

Original application September 11, 1945, Serial No. 615,568. Divided and this application November 25, 1949, Serial No. 129,252

4 Claims. (Cl. 102—20)

1

This invention concerns a new and useful apparatus for cutting pipe, which apparatus is particularly advantageous for use in limited confines such as well bores. In particular it concerns apparatus for employing specially shaped and specially disposed explosive charges for cutting well casing.

This application is a division of our copending application Ser. No. 615,568, filed September 11, 1945, entitled "Apparatus for Perforating and Cutting Well Casing" and assigned to the same assignee as the present application.

This invention is based upon the cutting action of a special type of explosive jet. This jet is the resultant effect of shaping the high explosive charge so that its end provides a concave surface facing the object to be penetrated, and in which, moreover, this concave surface is lined with an inert material such as a metal, ceramic or plastic. Such shaped and lined charges are very effective in creating holes in solid objects including steel, rock, cement, etc. The holes created are of considerable depth and diameter, although these may be varied over an appreciable range by varying the calibre of the explosive charge, its distribution and composition, the geometry of the concave shaped surface, the material and thickness of the liner, and the stand-off distance between the forward end of the charge and the target. We have utilized this effect in the apparatus of this invention useful for pipe-cutting operations in boreholes.

This invention is useful in cutting off well casing if it is desired to recover such casings above a cemented portion. Heretofore expensive mechanical devices have been inserted into the well on a rotatable drill stem to cut the casing around its circumference. In old wells, having no drilling equipment available, it has been common to use explosives to break off the casing. "Shooting" the casing by means of ordinary explosives often results in spreading of the broken end so that it is sometimes difficult or impossible to pull the pipe out of the hole. By the use of our invention employing properly-shaped explosive charges, a clean circumferential cut is easily and quickly made. It may likewise be used for cutting off collars between strings of casings. The apparatus is also applicable to cutting off drill pipe which has become stuck. It may further be used for cutting off any pipe, whether in the ground or above the ground, when conditions permit access only to the inside thereof.

It is accordingly an object of this invention to

2

provide an improved apparatus for cutting the casing of a borehole.

Another object of this invention is to provide apparatus for cutting the casing of a borehole by the use of a shaped high explosive charge.

Another object of this invention is to provide apparatus which achieves a highly efficient cutting action through steel or metal pipe.

Another object of this invention is to provide a pipe-cutting means employing the cutting effect of an explosive jet.

It is also an object of this invention to provide a method of cutting well casing which is substantially free from the disadvantage of forming burrs on the inside of the casing around the cut or slot made therein.

A still further object of this invention is to provide apparatus for severing pipe by the use of a specially-shaped high explosive charge.

Another object of this invention is to provide a means for severing pipe employing the cutting effect of an explosive jet.

These and other useful objects may be accomplished by the apparatus of our invention described in this specification, of which the accompanying drawings form a part; and in which:

Figure 1 shows a top plan view, partly in section, of a form of the explosive cartridge useful for severing pipe or casing;

Figure 2 shows a side view of the form of explosive cartridge of Figure 1;

Figure 3 shows a longitudinal section of an apparatus for cutting pipe by means of a shaped explosive charge; and

Figure 4 shows a section of the apparatus taken along line A—A of Figure 3.

In the apparatus of our invention the explosive is placed a certain distance from the target, namely, the wall of the pipe. The effect of the explosive is to create a cut or slot in the target by virtue of a specially shaped and lined cavity in the surface of the explosive facing the target. The target is not shattered. Virtually the whole penetrating power of the explosive used arises from the effect of the cavity plus liner formed in the surface of the explosive facing the material to be cut. This fact is apparently closely related to what has been previously known in the explosive art as the Munroe effect. While there are theories for this effect, it basically represents purely an empirical discovery. The theory suggests the possibility that an explosive jet of very high velocity is formed opposite the cavity and this jet has a strong penetrating or cutting effect.

The nature of the jet may be controlled and its

efficiency augmented by placing inert non-explosive material in the cavity as a liner.

The dimensions of the cut produced by a shaped explosive charge depend on the shape and the dimensions of the cavity; the kind, amount and distribution of high explosive in the charge; the nature of the confinement of the charge; the material, dimensions, and physical properties of the cavity liner; the distance between the base of the cavity and the surface of the target material; and the nature of the target material. By making proper selections of the above variables, the jet effect can be made to penetrate large distances into the target material.

The jet may be controlled by suitably varying other important parameters of the cavity liner, such as the included angle, liner material, liner weight, and stand-off from the target. It is true that an unlined cavity will give approximately the same target hole volume as the lined cavity, but the depth of the penetration is very much greater with the lined charge. The reason for this appears to be that the high explosive forms, from the liner material, a fine spray or jet which has very high penetrating power. The material of the cavity liner may be metallic, for example, steel, aluminum, brass, lead, copper; or it may be ceramic; or glass; or of plastic composition. The cavity need not of necessity have a straight-sided cross-section, but may be circular, parabolic, or may have other equivalent shapes.

Material of appreciable density within the cavity greatly diminishes the penetrating action of the charge merely because it prevents formation of the jet. When any dense material is some distance from the base of the cavity it is equivalent to a corresponding amount of the target in the path of the penetrating jet. In either case the residual penetration is greatly reduced. Therefore, material of appreciable density, for example water, must be excluded from the cavity, since the presence of such matter within the cavity greatly diminishes the penetrating action of the cavity charge. Thus, for work in liquids, the base of the cavity is provided with a suitable cover to prevent any liquid entering the cavity. The nature of the material surrounding the charge also influences the hole-formation performance considerably. An otherwise unconfined charge in a well would effectively be confined by any fluid present in the well. Thus, if unconfined shots are to be made in a fluid-filled well, the charges may be placed in a suitably-designed container which prevents the fluid from surrounding the charges.

The high explosive may be of any type such as pentolite, tetryl, TNT, etc., and may be augmented by any suitable chosen booster explosive. For example, tetryl could be used as a booster for pentolite, since the former is more sensitive to shock than the latter. The choice of high explosive material must be governed by the conditions under which it is to be used as is generally the case in any explosive application.

The apparatus encompassed by this invention makes use of linear wedge-shaped lined cavities to make linear cuts in the casing. In particular, to cut the casing around its circumference so as to permit pulling of the upper section, this apparatus uses a wedge-shaped lined cavity encircling a cylindrical stem of high explosive which may be solid or filled with a central inert core. On detonation of the high explosive along its inner boundary a uniform cut will be produced in the casing opposite the lined cavity. The

wedge angle, the nature of the liner, and "stand-off" of the cavity from the casing wall are chosen to fit the particular condition of the application.

Figures 1 and 2 show a lined cavity charge in which the cavity 50 extends circumferentially around the explosive charge 51. The cavity 50 is lined with lining material 52 and is closed by a cover 53. Detonation of the explosive is initiated at the center point 54 where there may be a small axial hole for inserting the fuse. Such a shaped charge may be employed in an apparatus for cutting casing, such as shown in Figures 3 and 4.

Figure 3 shows a longitudinal sectional view of a casing cutter in a well bore and Figure 4 is a transverse sectional view taken on the line A—A of Figure 3. A ring-shaped explosive charge 301 containing a peripheral trough or cavity 302 is lined by a liner 303. Well fluids are prevented from entering the cavity 302 by the cylindrical cover 304 which forms pressure-tight seals with upper plate 305 and lower plate 306 by means of gaskets 307 and 308. An axially-located metal piece 309 also makes pressure-tight seals with plates 305 and 306 by means of gaskets 310 and 311. The section of the piece 309 lying between plates 305 and 306 is enlarged and serves to prevent the collapse of these plates when the cutter is subjected to high external pressure. The piece 309 is attached to the lower plate 306 by means of the threads 312. The lock ring 313 serves to secure the top 305 on piece 309. A plurality of radial holes 314 in the piece 309 communicate between the charge 301 and an axial hole 315. The radial holes 314 and the portion of the hole 315 near the radial holes 314 are filled with explosive. An end plug 316 is attached to the lower end of piece 309 by means of the threads 317, and forms a pressure-tight seal with piece 309 by virtue of gasket 318. An electrically-actuated detonator 319 is in contact with the explosive contained in the hole 315. The lead wires 320 pass through the hole 315 to the fuze-chamber 321 which is attached to piece 309 by means of threads 322 and forms a pressure-tight seal with piece 309 by virtue of gasket 323. A cable 324 attached to the chamber 321 is the means of raising and lowering the cutter within the casing 325.

The assembly of the casing cutter is accomplished in the following way: The plug 316 is threaded into piece 309 and the latter into bottom plate 306. The explosive within piece 309 may be introduced at this time or previously. The ring-shaped charge 301, together with the liner 303, is then placed in position around the enlarged portion of piece 309 as is the cylinder 304. The top plate 305 and the lock-ring 313 are then placed in position and secured. The electric detonator 319 is then inserted into the bore 315 so as to be in contact with the explosive, and the leads 320 are connected to the fuze-chamber 321 after which the latter is threaded onto the upper end of piece 309.

The fuze-chamber 321 may contain mechanisms which arm and disarm the device under appropriate conditions, and a mechanism for locating the ends of casing segments if it is desired to cut away the casing at any fixed distance relative to a collar.

The operation of the device is as follows: When the cutter has been lowered to the proper position in a well and when all arming devices in the fuze-chamber have functioned, an operator on the surface sends an electrical impulse to the det-

onator 319 by means of the cable 324 and a battery or other source of voltage at the surface. The detonation wave initiated on the axis by the detonator is propagated through the channels 314 to the charge 301 which, on detonation, severs the casing 325 along the plane A—A.

The explosive may be any suitable high-explosive such as 50-50 pentolite, and may be formed in any convenient manner such as casting or pressing. The annular region bounded by the cylinder 304, the liner 303 and the plates 305 and 306 must be kept free of any dense matter of any kind. The cutting ability of the device depends on the shape, thickness, and material of the liner 303, the stand-off distance measured from the outermost position of the liner to the target, and the material of the target itself. We have discovered that the width of the charge 301, i. e., the separation between plates 305 and 306 should be approximately 1½ to 3 times the combined thickness of the cylinder 304 and casing 325.

We have discovered that steel liners 303, Figure 3, having a cavity angle in the range of 80° to 140° and with thicknesses ranging from 0.02 to 0.04 charge width are most satisfactory. The corresponding stand-off range is preferably from 0 to 2 charge widths.

Liner 303, Figure 3, may alternatively be made of aluminum. In this case the desirable cavity angle is in the range of 70° to 140° with thickness ranging from 0.04 to 0.10 times the charge width. The stand-off may range from 0.5 to 4.0 times the charge width for best results, the larger stand-offs being associated with the larger cavity angles.

We have shown the cutting charge liner to have a strictly angular cavity shape as drawn in Figures 1 to 4, but it may alternatively be parabolic, circular, or have other shapes. Furthermore, liners may be made of materials besides steel or aluminum, these being cited merely by way of example. The liner of the cutting charge cavity may be any of the inert materials previously mentioned.

What we claim is:

1. Apparatus for cutting pipe comprising an explosive charge in the shape of an annular ring having an outwardly-directed cavity, an explosion-confining annular lower plate in contact with the lower side of said ring, an explosion-confining annular upper plate in contact with the upper side of said ring, support means passing through the central openings of said ring and said plates supporting said plates in spaced relationship, said support means having an axial channel and a plurality of radial channels from said axial channel to the inner surface of said ring, an explosive in said axial channel and in said radial channels, and means for initiating detonation of said explosive in said axial channel.

2. Apparatus for cutting pipe comprising an explosive charge in the shape of an annular ring

having an outwardly-directed cavity, an explosion-confining annular lower plate in contact with the lower side of said explosive ring, an explosion-confining annular upper plate in contact with the upper side of said explosive ring, support means passing through the central openings of said explosive ring and said plates supporting said plates in spaced relationship, detonating means in said support means, and an explosive-filled channel leading from said detonating means to the inner surface of said explosive ring.

3. Apparatus for cutting pipe comprising an explosive charge in the shape of an annular ring having an outwardly-directed cavity, an explosion-confining annular lower plate in contact with the lower side of said explosive ring, an explosion-confining annular upper plate in contact with the upper side of said explosive ring, support means passing through the central openings of said explosive ring and said plates supporting said plates in spaced relationship, a cover over the cavity of said explosive ring sealed against said upper and lower plates, detonating means in said support means and an explosive-filled channel leading from said detonating means to the inner surface of said explosive ring.

4. Apparatus for cutting pipe comprising an explosive charge in the shape of an annular ring having an outwardly-directed cavity, an explosion-confining annular lower plate in contact with the lower side of said explosive ring, an explosion-confining annular upper plate in contact with the upper side of said explosive ring, support means passing through the central openings of said explosive ring and said plates supporting said plates in spaced relationship, a liner contiguous to the cavity of said explosive ring, a cover over the cavity of said explosive ring sealed against said upper and lower plates, detonating means in said support means, and an explosive-filled channel leading from said detonating means to the inner surface of said explosive ring.
